United States Patent

Des. 239,511

Patented Apr. 13, 1976

239,511

DIGITAL WATCH CASE

Tandy Plez Watson, 2711 Minert, 268,
Dallas, Tex. 75219

Filed July 15, 1974, Ser. No. 488,283

Term of patent 14 years

Int. Cl. D10—02

U.S. Cl. D10—38

FIG. 1

FIG. 2

FIG. 5

FIG. 3

FIG. 4

FIG. 1 is a top left front perspective view of a digital watch case showing my new design;

FIG. 2 is a top plan view thereof;

FIG. 3 is a front elevational view thereof;

FIG. 4 is a right side elevational view thereof;

FIG. 5 is a bottom plan view thereof.

I claim:

The ornamental design for a digital watch case, substantially as shown and described.
